UNITED STATES PATENT OFFICE.

GEORGE N. JACOB, OF BROOKLYN, NEW YORK, ASSIGNOR TO HANLON & GOODMAN CO., OF NEW YORK, N. Y., A CORPORATION OF NEW YORK.

BRUSH.

Application filed January 16, 1925. Serial No. 2,789.

This invention relates to brushes, and more particularly to bristle brushes.

An object of the invention is to produce a brush having many of the advantages of a 5 pitch set brush.

A further object is to produce a brush in which the bristles are securely held to the handle, and one that may be produced in an economic and efficient manner.

10 Heretofore among the many brushes that have been produced one of the most reliable has been the so called pitch set brush which is comparatively expensive. This is a brush wherein separate individual units of bristles 15 were each positioned in a hole in the base of the brush and held therein by suitable means such as a plastic.

In accordance with my invention a brush is produced which possesses many of the advantages of this type of brush, but is free 20 from the objections of the older type.

Briefly stated the brush in its preferred form comprises a bunch of bristles surrounded at one end by a member whose interior is 25 provided with a plurality of grooves substantially parallel to the bristles, and the bristles are preferably impregnated at this end with a plastic. An expanding member is positioned in the bunch of bristles at the 30 impregnated end and serves to force the bristles outwardly toward this encircling member and to force portions of the bunch of bristles into the interior grooves formed in the encircling member, thereby causing 35 the bristles to be held in place not only by the plastic but additionally by the clamping action between the expanding member and the encircling member.

Those portions of the bunch of bristles 40 forced into the grooves are formed into small units, which stand out from the bunch of bristles, presenting thereby a serrated surface adjacent the encircling member. These serrations act as key members to firmly lock 45 the bristles in position.

The invention consists in the product hereinafter described in reference to certain preferred embodiments thereof, and the invention will be more particularly pointed out 50 in the appended claims.

In the drawings Fig. 1 is a side elevation showing parts of the brush at one step of manufacture.

Fig. 2 is an end elevation of Fig. 1.

Fig. 3 is a side elevation showing the same 55 parts at a subsequent step.

Fig. 4 is a cross section at 4—4 of Fig. 3.

Fig. 5 is a plan view of Fig. 3.

Fig. 6 is a modification in plain view.

Fig. 7 is a view in side elevation showing 60 a completed brush with parts broken away.

Fig. 8 is a section at 8—8 of Fig. 7.

Fig. 9 shows a modified form of brush in side elevation with parts broken away.

Fig. 10 is a section at 10—10 of Fig. 9. 65

Referring to the drawings, and more particularly to Figs. 1-6; first I take a suitable quantity of loose bristles, which may be gauged such as by weighing, and arrange them into a bunch 1 (Figs. 1 and 2) that 70 will be of sufficient size for the brush to be made. I next surround the bunch of bristles, at a point intermediate its ends, with an encircling member or band 2 made of any suitable material or materials, such for example 75 as wood, metal, composition or the like, provided with grooves 3 (Figs. 5, 6 and 10) which extend in a direction substantially parallel to the bristles. With the encircling member 2 slipped back from one end of the 80 bristles a distance greater than the height of the member 2, this end of the bunch 1 is dipped in a suitable plastic such as rubber a depth preferably substantially equal to the height of the member 2; forming thereby 85 an impregnated portion designated (Figs. 1 and 2) as 4. Those portions of the bristles so coated will be termed the roots of the bristles. By suitable means, such as a drying oven, the end 4 is partially solidified 90 by having a part of the solvent driven off. With a suitable instrument such as the cleaving knife 5 this plastic-impregnated end of the bunch is now separated lengthwise of the 95 impregnated end and in the cleft so formed the expanding bristle-member or wedge 6 is inserted and the knife 5 withdrawn. The impregnated end 4, with the expanding member 6 in position is now placed in a suitable die (not shown) and this end is 100 pressed to the desired size and shape so that the member 2 may be forced around it. The encircling member 2 is now forced up until it surrounds the dipped end 4 and expanding member 6 to thereby force exterior portions of the bunch of bristles into the grooves 105 3 and thereby firmly lock or key the outer bristles in a fixed stable position within

these grooves; while all of the bristles are firmly squeezed in between the encircling member 2 and the expanding member 6, such as at 7. The brush so far formed is now 5 preferably placed on a vulcanizing table to thereby harden the plastic, as by curing. The bristles, the encircling member and the expanding member have now been united into substantially a single unit as shown in 10 Figs. 3, 4, 5 and 6. The final step now consists in affixing a suitable handle (Fig. 7) 8. The handle 8 is provided with a recess formed within the depending sleeve 9. This 15 recess has an inside contour adapted to receive the encircling member 2 which carries the root end of the bristles and the wedge 6 united therewith by means of the plastic binder. The united end of the bristles is now inserted in this recess as shown in 20 Fig. 7, and is secured therein by any suitable means such for example as by the nails or screws 10. In addition to this means of fastening, or in place thereof fastening means such as screws or nails 11 may be 25 inserted through the member 6 into the handle 8. In either event the bristle unit will be firmly held to the handle.

Instead of a single wedge or expanding member 6 as shown in Figs. 1, 2, 3, 4, 5, 7, 30 and 8 it will be obvious that two members such as 6' and 6'' may be used as shown in Figs. 6, 9 and 10. Also instead of forming the encircling member from one piece of wood or other material it may be made as shown 35 in Fig. 10 of two or more pieces 2' and 2'' joined together by suitable means such as a metal strip or band 2''' and when so made instead of inserting the bristles through the member so formed, the member may be assembled about the bristles if desired. In 40 this case the handle 8' is not recessed but is provided with a reduced portion 9' over which the band 2''' will fit and to which it is then attached by suitable means such as 45 nails or screws 10', it being understood that the band 2''' in this case is of greater width than the depth of the members 2' and 2''. Also where one member such as 2 is used a band similar to 2''' may be used to attach the 50 tuft unit to a handle such as the handle 8'.

By this method a brush is produced in 55 which the bristles are firmly held and will not shed. In addition to the plastic binder the expanding wedge member 6 holds the bristles firmly outwardly pressed against the encircling member 2 and added to this the grooved portions in which a portion of the outer bristles are seated form individual pockets or recesses in which small units of 60 bristles are firmly held, thus imparting add-

ed strength to the bristle unit. These serrated portions of the bunch which are formed in the interior grooves of the member 2 prevent the sidewise movement of the bristles and by being divided into smaller 65 units with interposed portions of the member 2 the expansion and contraction of the plastic is accommodated or permitted by the yield of the member 2.

Having thus described my invention with 70 particularity with reference to certain preferred forms thereof, it will be obvious to those skilled in the art, after understanding my invention, that other changes and modifications may be made therein without departing from the spirit and scope of the invention; and I aim in the appended claims 75 to cover such changes and modifications as are within the spirit and scope of the invention.

What I claim is:

1. A bristle brush comprising an oblong band member embracing and securing, the butt end of a bunch of bristles, said band being provided interiorly at least along its 85 longer sides with a plurality of substantially semi-circular spaced grooves running substantially parallel to the bristles, the diameter of said grooves being small with respect to the width of the brush, a core disposed 90 within said butt end of the bunch of bristles and running lengthwise of said oblong band, said bunch of bristles comprising one undivided continuous tuft cemented and permanently formed in situ under pressure of said 95 core, the periphery of the bunch of bristles being firmly secured and also serrated by reason of said grooves, and a handle having means for engaging said band member.

2. A bristle brush comprising an oblong 100 band member embracing and securing the butt end of a bunch of bristles, said band being provided around its interior surfaces with a plurality of spaced grooves running substantially parallel to the bristles, said 105 grooves being intercepted by blunt surface areas, a core disposed within said butt end of the bunch of bristles and running lengthwise within said oblong band, said bunch of bristles comprising an integral tuft filling 110 said band and cemented and permanently formed in situ under pressure of said core, the periphery of said tuft being firmly secured and also formed with spaced ridges by 115 reason of said spaced grooves, and a handle member secured to said band member.

In testimony whereof I have signed my name to this specification.

GEORGE N. JACOB.
